UNITED STATES PATENT OFFICE.

EZRA STIEDINGER, OF FAIRBURY, ILLINOIS.

MAIL-BAG CATCHER AND DELIVERER.

No. 914,193.

Specification of Letters Patent.

Patented March 2, 1909.

Application filed July 7, 1908. Serial No. 442,995.

To all whom it may concern:

Be it known that I, EZRA STIEDINGER, a citizen of the United States of America, residing at Fairbury, in the county of Livingston and State of Illinois, have invented new and useful Improvements in Mail-Bag Catchers and Deliverers, of which the following is a specification.

This invention relates to mail bag catchers and deliverers, and one of the principal objects of the same is to provide simple and efficient means for delivering a mail bag and simultaneously catching a bag to be thrown into the open door of a mail car on a moving train.

Another object of the invention is to simplify the construction of the holders for the mail bags at the station to take the place of the usual cranes.

These and other objects may be attained by means of the construction illustrated in the accompanying drawing, in which,—

Figure 1 is a perspective view of a mail bag catcher and deliverer made in accordance with my invention. Fig. 2 is a front elevation of the bag-suspending device.

Referring to the drawing, the numeral 1 designates a mail car, and 2 is the door opening therein. On opposite sides of the door opening 2 brackets or keepers 3 are secured, and mounted pivotally in said keepers is my mail bag catcher and deliverer. Said catcher and deliverer consists of a rod or bar 4 pivoted in the keepers 3 at its opposite ends and 35 provided with a centrally disposed hand lever 5 for swinging the same outward when it is desired to deliver and catch a bag. Connected to the rod 4 is an outwardly extending arm 6, and formed on the outer end of said arm 40 is a fork consisting of the member 7 to which a spring 8 is secured and the member 9 having a curved outer end 10. The fork extends from one side of the arm 6, while upon the opposite side a finger 11 projects, said finger having a bend 12 at a point near the arm 6.

In lieu of the usual crane at the station I provide a receiver consisting of a box-like structure 13 having a central partition 14, open ends 15 and a top comprising two members 16 having rounded corners 17, thus providing an entrance throat for the mail bag supporter, said throat leading into a slot 18 which extends from the opposite ends of the 55 receiver to the partition 14.

The mail bag supporter consists of a bar 19 having connected to its upper end a loop 20 and a spring 21 below the loop. At the lower end a hook 22 is provided to engage the staple or bill on the end of the mail pouch 23. A 60 spring 24 is also secured to the bar 19 immediately above the hook 22. These mail bag supporters are used both for the bag to be delivered at a station and the bag to be taken up by the mail car, and it will be seen in Fig. 65 1 that the mail bag 23 is placed in the fork to be delivered at the station, while the mail bag 25 is placed on the opposite side of the partition 14 to be caught by the finger 11 entering the loop 20 to carry the bag out of the slot 18 70 on the finger 11 to be swung into the mail car. To prevent the loop 20 from displacement in the fork I have provided a keeper consisting of a wire finger 4^a which holds the bag-suspending device in proper position.

My invention is of a simple character, cannot readily get out of order, and will operate smoothly and efficiently without chance of injury to either the device or to the mail bags.

I claim:—

1. A mail bag deliverer and catcher comprising a rod pivotally connected to the mail car and provided with a lever, an arm, a fork and a finger, a mail bag support consisting of a bar having a loop at one end, a spring below the loop, a hook at the opposite end, a receiver consisting of a box-like structure having a slotted top, a partition, and a mouth leading into said slot.

2. In a mail bag deliverer and catcher, a rod pivoted to the mail car and provided with a fork and finger, in combination with a mail bag support consisting of a bar having a loop at one end and a hook at the other, and a receiver having a slotted top and a partition.

3. A mail bag catcher and deliverer comprising a pivoted rod carrying a fork and a finger, in combination with a mail bag support provided with a loop at one end and a hook at the other, and a receiver provided with a slot, a central partition and an enlarged mouth at each end.

In testimony whereof I affix my signature in presence of two witnesses.

EZRA STIEDINGER.
